(57) **CLAIM**

The ornamental design for a scissors cover as shown and described.

DESCRIPTION

FIG. 1 is a perspective view of scissors cover showing my new design;

FIG. 2 is a front view thereof;

FIG. 3 is a rear view thereof;

FIG. 4 is a right view thereof;

FIG. 5 is a left view thereof;

FIG. 6 is a bottom view thereof;

FIG. 7 is a top view thereof; and,

FIG. 8 is a perspective view showing my new design arranged with a support unit.

The broken lines in the drawing are for illustrative purpose only and shows the portion that forms no part of the design to be claimed.
